UNITED STATES PATENT OFFICE.

FRANCOIS FAVARGER, OF NEUCHATEL, SWITZERLAND, ASSIGNOR, BY MESNE ASSIGNMENTS, TO NATIONAL TELEREGISTER CORPORATION, OF NEW YORK, N. Y., A CORPORATION OF DELAWARE.

ELECTRIC SIGNALING APPARATUS.

Application filed October 31, 1924, Serial No. 747,140, and in Switzerland November 12, 1923. Renewed September 23, 1927.

This invention relates to electric signaling apparatus and more particularly to apparatus for connecting a signaling circuit to a source of current during an interval, or a series of intervals, of accurately measured duration.

10 The invention is particularly adapted to the transmission of impulses or groups of impulses of accurately measured length which may, according to certain phases of the invention, also be separated by interruptions of equal length. The apparatus is therefore adapted for use in the operation of signaling circuits, as for example in the control of electromagnetically operated indicating devices located at a distance.

20 The objects of this invention include the provision of apparatus and equipment of the above indicated class which is dependable, efficient and rapid in operation.

25 Various further and more specific objects, features and advantages will clearly appear from the detailed description given below taken in connection with the accompanying drawing which forms a part of this specification and illustrates merely by way of example one of the various possible embodiments of the invention.

30 The invention consists in such novel features, arrangements and combinations of devices and circuits as may be shown and described in the apparatus herein disclosed by way of example, only as illustrative of a preferred arrangement.

35 The drawing illustrates diagrammatically the particular example of the invention hereinafter described.

40 In the drawing the devices indicated by the numerals 1 and 1' may comprise electromagnetically operated or other electrically operated indicating units, such for example as the stock, commodity or exchange indicating units shown in applicant's copending application Serial No. 613,012, filed January 16, 1923, corresponding to British Patent 192,055, accepted April 3, 1924.

45 It will be understood that the indicating members 1 and 1' illustrate by way of example two of a relatively large group of indicators all actuated by either the same apparatus as hereinafter described, or apparatus similar thereto and associated therewith. Where a large group of such devices are to

be controlled from a distance, particularly where control is to be effected through selecting mechanism as referred to in applicant's application Serial No. 613,012 above mentioned, it is desirable for dependable operation that the actuating impulses shall be of accurately measured duration. Yet it is in 55 many cases desirable to provide manually operable means for initiating such impulses from time to time more or less irregularly. The apparatus hereinafter described provides means for connecting a source of current to the signaling circuit running to such indicators so that the desired impulses or groups of impulses of accurately measured duration and/or frequency may be transmitted to the indicators either directly as indicated diagrammatically in the accompanying drawing, or through relays or other devices and arrangements.

50 In the present example the device 1 is connected to a generator or source of current 2 by means of a wire 3 and also by means of a wire 4, by way of a normally open switch 5, 6, formed by a pair of flexible blades. The blade 6 forms moreover a contact with the flexible blade 7, which is connected with the positive terminal of the generator 2 through the medium of conductors 8, 8' and a contact making device 9, 10, consisting of a pair of flexible blades. The contact 10 affords contact with a flexible blade 11 fitted with a 75 push button 12. The blade 11 is connected to the negative terminal of the generator by conductors 14, 15, 16 and 3. Between the conductors 15 and 16 is inserted a small rotary electric motor 17, which motor controls 80 a switch or contact device 18, 19 and a contact making device 20, 21, actuated alternately by a radially extending lug 22 on the motor shaft.

85 It will be noted in the drawing that the motor 17 is provided with a series field winding, thus insuring ample torque to promptly and almost immediately bring the motor to full speed after current is applied thereto, and since the mechanical load on the motor 95 is negligible, the motor speed will remain uniform. Accordingly, the time intervals between successive actuations of the contact making devices operated by the motor will also be uniform and of an accurately measured predetermined duration. It will be 100 105

appreciated that other forms of motors, either rotary or of other types, might be substituted according to certain phases of the invention.

5 This contact and this switch are arranged in series and connected to the negative terminal of the generator and to the conductor 8 and to the contact 7, through the medium of two relays 23, 24, interposed in the line 10 25, 26. Each relay has armature 27 and 28 respectively. The armature 28 is intended to engage the contact 7 and to close simultaneously the associated contacts 7, 6 and 6, 5. The armature 27 has for its object to close 15 simultaneously the two associated contacts 29, 30 and 31, 32. The contact 29, 30 closes the following circuit:—Generator 2, positive terminal—4—30—29—15—motor 17—16—3—generator 2, negative terminal, while the 20 contact 31, 32, closes a circuit comprising the relays and switch 18, 19. This circuit is as follows:—Generator 2, positive terminal—4—6—7—24—26—23—25—18—19—33—31—32—3—generator 2, negative terminal.

25 A condenser 34 may be arranged in parallel with the switch 18, 19 in the ordinary manner to reduce arcing and contact deterioration.

The operation of the apparatus described is as follows:

30 When the push button 12 is actuated either by hand or automatically, by means of a cam or other suitable mechanism provided for that purpose, the contact devices 10, 11 and 10, 9 simultaneously close their corresponding circuits.

35 The first of these circuits (generator 2, positive terminal—4—8'—10—11—14—15—17—16—generator 2, negative terminal) starts the motor 17, which rotates in the direction indicated by the arrow, while the second circuit (generator 2, positive terminal—4—8'—10—9—8—24—26—23—25—18—19—20—21—generator 2, negative terminal) remains open between 20 and 21. The latter is closed only at the moment when the lug 22 of the motor closes the contact 20, 21. At this moment the relays 23, 24 are excited, as a result of which the armatures 27 and 28 actuate the associated contacts 29—30, 31—32 and 7—6, 6—5. For this reason the relays 40 23 and 24 continue to be excited, although the contact 20, 21 may be opened again after the passage of the lug 22 of the motor, because the exciting current passes then into the parallel-circuit:—Generator 2, positive terminal—4—6—7—24—26—23—25—18—19—33—31—32—3—generator 2, negative terminal.

45 On the other hand the contacts 5, 6 close the following circuit:—Generator 2, positive terminal—4—6—5—1—3—generator 2, negative terminal.

50 The electro-magnet 1 (which represents the well-known electromagnet of a receiving apparatus and may be provided with either a pivoted or rotatable armature for controlling

any desired indicating mechanism, such for instance as graduated disks or drums, or needles) is then actuated by the impulse of current which continues until the motor 17 actuates the switch or contact device 18, 19 70 and thus interrupts the exciting circuit of the relays. The latter being no longer excited the contacts which they actuated are opened again. This interruption of the circuit of the relays continues until the motor 17 again 75 closes the contact 20, 21, the switch or contact device 18, 19, being also closed. At this moment the relays are again excited so that the operations described are again repeated. Thus the excitation of the relays continues 80 from the moment when the contact 20, 21 is closed, until the switch or contact device 18, 19 is opened. Inversely, the interruption of the current in the relays continues from the moment when the switch or contact device 18, 19 is opened until the contact 20, 21 is again closed. There may thus be obtained either a single impulse or an alternation of flow and interruption of current in the relays of perfectly regular succession, the frequency of 85 these alternations being a function of the speed of rotation of the motor 17, a series of impulses being obtained either by holding down the manual control key 12 during more than one revolution of the motor rotated contact device 22 or otherwise.

90 The device continues to operate as long as the starting contacts 11, 10 and 10, 9 are held closed. The operator holds the push button 12 depressed until the electromagnet 1 has 100 received a predetermined number of intermittent current impulses. The number of current pulsations emitted by the motor may be controlled at the point of emission by the provision of a counter or other suitable instrument (not shown). If the pressure exerted on the push button 12 is interrupted the motor 17 continues to rotate until the exciting circuit of the relays 23, 24 is interrupted by the opening of the switch 18—19, because as 105 long as the relays are excited the current supplying the motor 17 passes through what may be termed the second or parallel motor circuit:—Generator 2, positive terminal, —4—30—29—15—17—16—3—generator 2, negative terminal. Thus the duration of the last 110 impulse of current actuating the relays 23, 24 is accurately measured and if desired is exactly equal to the duration of each of the preceding impulses, at whatever moment the 115 push button 12 is pressed or is released.

120 In the particular arrangement shown, the excitation of the electro-magnets or equivalent devices 1, 1' is thus dependent on the operation of the relay 24 in such manner 125 that they receive intermittent currents and interruptions of durations always equal inter se, at whatever moment the button 12 is pressed or is released.

130 It will thus be observed that the relays

at 23 and 24 cooperate with each other, whereby the relay 23 to an extent controls the operation of the relay 24 by virtue of the operation of the contact device 31, 32, which is in effect a relay "stick" switch, replacing switch 20, 21 after each impulse is initiated. In the particular example shown, the relay at 24 also to an extent at times controls the relay at 23 by virtue of the contact making device 6, 7, which is also a relay "stick" switch. In addition, the relay at 24 has a circuit interrupting device, namely, the switch at 5, 6, controlling the application of current to the signaling circuit of the device 1 or its equivalent. In addition, the relay at 23, once the manually operable switch 10, 11 is closed, maintains the motor 17 in operation by virtue of the "stick" switch at 29, 30.

It will be readily understood that instead of a single electromagnetic indicator, a plurality of such indicators may be operated from the conductor 3 or its equivalent. The operating magnet and relay connections for one of such additional indicators is illustrated in the drawings in dotted lines. Also an additional push button and associated contacts are shown for the control of the same. It will be understood that numerous additional indicator units may be connected in like manner and that all of the same may be controlled from the single motor circuit and relay 23 in the same manner as above described. That is, when the operator desires to actuate a certain indicator and the corresponding control relay therefor, he presses the corresponding push button. The relay 23 may therefore be employed to act as a motor relay common to a plurality of relays similar to relay 24.

While the invention has been described in detail with respect to a particular preferred example thereof which gives satisfactory results, it will be understood by those skilled in the art, after understanding the invention, that various changes and modifications may be made without departing from the spirit and scope of the invention, and it is intended, therefore, in the appended claims to cover all such changes and modifications.

What is claimed as new and desired to be secured by Letters Patent of the United States is:—

1. A signal transmitting apparatus, comprising a source of electrical current, a motor in electrical connection with said source, a pair of relays connected in series with said source, a system of normally open contacts in the motor and relay circuits adapted to close said circuits and cause rotation of the motor, a normally open switch and a normally closed switch in the relay circuit, means carried by the motor for closing and thereafter opening said normally open switch and opening and closing said normally closed

switch once during each revolution of the motor, a second circuit including said normally closed switch and connecting said relays in series with the source of current, a system of normally open contacts in said second circuit, and means operable by the relays for closing said contacts and causing current to continue to pass through the relays after the normally open switch has been opened and before the opening of the normally closed switch. 76

2. Apparatus for connecting a signaling circuit to a source of current during an interval of accurately measured duration, comprising an electric motor driven rotatable contact operating member, a manually controlled starting circuit for the motor, a second motor circuit controlled by said member for continuing the rotation of the member until the same is restored to a rest position 85 after termination of the measured interval, and a pair of cooperating relays having circuits controlled by contacts at predetermined points along the path of said member and successively operatively engaged by the same 90 respectively at the beginning and ending of said interval, said relays and contacts being operatively associated to connect, and maintain connected, the signaling circuit to the source of current during the said interval. 95

3. Apparatus for connecting a signaling circuit to a source of current during an interval of accurately measured duration, comprising an electric motor driven rotatable contact operating member, a manually controlled 100 starting circuit for the motor, a second motor circuit controlled by said member for continuing the rotation of the member until the same is restored to a rest position after termination of the measured interval, and a pair of cooperating relays having circuits controlled by contacts at predetermined points along the path of said member and successively operatively engaged by the same respectively at the beginning and ending of said interval, said 110 relays and contacts being operatively associated to connect, and maintain connected, the signaling circuit to the source of current during the said interval and also to maintain said second motor circuit. 115

4. Apparatus for connecting a signaling circuit to a source of current during an interval of accurately measured duration, comprising an electric motor driven rotatable contact operating member, a manually controlled starting circuit for the motor, a pair of cooperating relays having circuits, controlled by contacts at points along the path of said member and successively operatively engaged by the same respectively at the beginning and ending of said interval, a second motor circuit for continuing the rotation of the motor and said member until the same is restored to a rest position after termination 125 of the measured interval, one of said relays 130

having a "stick" switch controlling said second motor circuit and also a "stick" switch controlling the operation of the other relay, said relays and contacts being operatively associated to connect, and maintain connected, the signaling circuit to the source of current during the said interval.

5. Apparatus for connecting a signaling circuit to a source of current during an interval of accurately measured duration, comprising an electric motor driven rotatable contact operating member, a manually controlled starting circuit for the motor, a pair of cooperating relays having circuits controlled by contacts at points along the path of said member and successively operatively engaged by the same respectively at the beginning and ending of said interval, a second

motor circuit for continuing the rotation of the motor and said member until the same is restored to a rest position after termination of the measured interval, one of said relays having a "stick" switch controlling said second motor circuit and also a "stick" switch controlling the operation of the other relay, the other of said relays controlling a disconnecting switch in said signaling circuit and also having a "stick" switch controlling itself, said relays and contacts thus being operatively associated to connect and maintain connected the signaling circuit to the source of current during the said interval.

In testimony whereof I have signed my name to this specification.

FRANÇOIS FAVARGER.
